UNITED STATES PATENT OFFICE.

ELI KEARSLEY, OF PHILADELPHIA, PENNSYLVANIA.

FEEDER FOR CARDING-MACHINES.

SPECIFICATION forming part of Letters Patent No. 437,304, dated September 30, 1890.

Application filed March 21, 1890. Serial No. 344,744. (No model.)

To all whom it may concern:

Be it known that I, ELI KEARSLEY, a citizen of the United States, residing at Philadelphia, in the county of Philadelphia and 5 State of Pennsylvania, have invented certain new and useful Improvements in Feeders for Carding-Machines; and I do hereby declare the following to be a full, clear, and exact description of the invention, such as will enable 10 others skilled in the art to which it appertains to make and use the same.

The invention relates to feeders for carding-machines; and it consists in certain improvements in the construction of the same, as 15 hereinafter described and claimed. As commonly constructed, the feeder is provided with a carrier formed of an endless toothed apron, which is located in the feed-box and carries the wool or other stock upward therefrom to 20 be fed to the carding-machine. When the box is full, the pressure of material against the carrier is the greatest, and the material in the box is taken up more rapidly than when the box is nearly empty. Sometimes 25 the feed-box becomes exhausted of stock without it being known until the card shows light work. The consequence is that there is often trouble about uneven yarn, and to remedy this I provide a feed-board which is automatic in its operation and is adapted to keep 30 the stock in the feed-box pressed to the carrier with a uniform pressure while any material remains in the box; and in order that operatives shall know when the contents of 35 the feed-box are nearly exhausted certain devices are connected with the feeder by means of which an alarm is sounded when the box is nearly empty.

In the accompanying drawings, Figure 1 is 40 a plan view of a feeder for carding-machines provided with my improvements. Fig. 2 is a central vertical section of the same. Fig. 3 is a front view, and Fig. 4 is a side view of the same.

45 A designates the feed-box, in which is placed the stock or material to be fed to the carding-machine.

B indicates a carrier, formed of an endless toothed apron, which moves on rollers α for 50 conveying the stock upward from the feed-box.

Within the feed-box is placed a feed-board C, the lower end of which is pivoted at α , so 55 that the board may be swung toward or from the carrier B. To the upper end of the board

C are fastened the bent arms b and b' , to which are attached the weighted cords c , which extend along the sides of the feed-box over pulleys d . A bracket f is slotted and adjustably secured to the bent arm b by a clamp-screw f^2 , and a spring-rod g , which carries a bell h , is fixed in position for contact with the said bracket when the board C has been moved a certain distance toward the carrier B. A catch e projects from the upper end of the feed-board and connects with a latch or pivoted lever k when said board is swung forward. The feed-box may then be filled with material to be fed to the card. The lever k is disconnected from the catch e by the action 70 of a slowly-rotating cam m , which impinges against an arm of a pivoted lever n , and the latter in turn raises one end of the lever k , and thus releases the feed-board. The feed-box being filled, the contents are pressed by 75 the board C, the latter being steadily moved toward the carrier by the weights s of the cords c , as the material is taken from the box by the carrier B. When the contents of the box are nearly exhausted, the arm or bracket 80 f , having been adjusted on the arm b , comes in contact with the spring-rod g , and the bell h is rung and continues ringing until the board C is moved back from the carrier, when the feed-box may be refilled. The bell is kept 85 ringing by the action of a cam p on one end of the shaft r .

I claim—

1. The combination, with the feed-box of a feeder, of a pivoted feed-board C, provided 90 with bent arms, weighted cords connected with said bent arms and adapted to move said feed-board, an arm or bracket carried by one of said bent arms, the cam p , and a spring-rod provided with a bell, said rod being fixed 95 in position for contact with said bracket on the forward movement of the feed-board, substantially as set forth and described.

2. The combination, with the feed-box and pivoted feed-board C, provided with catch e , 100 pivoted levers k and n and cam m , the latter being adapted to engage the lever n , which is adapted to move the lever k from catch e , substantially as set forth and described.

In testimony whereof I have affixed my signature in presence of two witnesses.

ELI KEARSLEY.

Witnesses;

J. HOHNE,

H. BRADSHAW.
